UNITED STATES PATENT OFFICE.

WILLIAM HITT BOGGS, OF COVINGTON, OHIO.

FOLDING SWING.

SPECIFICATION forming part of Letters Patent No. 660,179, dated October 23, 1900.

Application filed April 21, 1900. Serial No. 13,677. (No model.)

To all whom it may concern:

Be it known that I, WILLIAM HITT BOGGS, a citizen of the United States, residing at Covington, in the county of Miami and State of Ohio, have invented certain new and useful Improvements in Folding Swings; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to a folding swing, and has for its object the construction of a swing that is both simple and inexpensive and one which may be readily and quickly placed in position for use or when desired is susceptible of being knocked down and folded in a compact form for transportation or storage without the removal or disconnection of any of its parts.

To this end the invention consists, essentially, in the peculiar and novel combination and arrangement of the various parts, as will be more fully described hereinafter and pointed out in the subjoined claims in accordance with the statutes in such cases made and provided therefor.

Referring to the accompanying drawings, illustrating my invention, and in which like numerals of reference refer to corresponding parts throughout the several views, Figure 1 is a side elevation of my improved swing when placed in position ready for use. Fig. 2 is a plan view of the same, and Fig. 3 is an end or rear elevation. Fig. 4 is a view of the swing when knocked down and folded ready for storage or transportation. Fig. 5 is a detail view, on a slightly-enlarged scale, showing the manner in which the legs or standards of the seat and back are supported on the lower cross-rods of the platform, also the manner and position of the sections of the platform when "breaking joints" while the swing is being knocked down or folded; and Fig. 6 is an enlarged view in detail of a portion of one of the legs or standards of the seat and a cross-section of the lower cross-rod of the platform which supports it.

In describing my invention in detail and having reference to the various parts thereof

by means of the aforesaid numerals of reference as employed throughout the several views of the accompanying drawings, 1 represents the cross-bars, which are arranged in pairs or sets on each side of the swing, and thus support it, the cross-bars of each pair extending at an incline from their base to their top, where they are connected from one side of the swing to the other by transverse braces 2, said cross-bars intersecting or crossing each other in the form of a "sawbuck," and, as shown in Figs. 2 and 3 when looking at either end of the swing, the cross-bars on either side thereof will extend far enough outwardly at their base as to a lateral position to leave full and sufficient space between for the clear and free movement of the swing in its sweep.

3 are short braces which extend a sufficient distance from the base up the side of and are connected to each of said cross-bars, so as to assist, in connection with transverse bars 4, which extend across each end of the swing at its base and are firmly attached or fastened to the ends of said cross-bars and said short braces, in forming a firm solid base-support for the ends of the cross-bars. A central brace-rod 5 passes through each of said cross-bars from pair to pair at a point where the bars of each pair intersect and extends transversely from one side of the swing to the other and is provided with nuts and washers 6 or other suitable means, which thus helps to retain the pairs in position and pivotally connects each pair or set of cross-bars one with the other, and thus permits of the swing being folded together, as shown more particularly in Fig. 4.

7 represents the vertical or perpendicular standards or bars, having their ends beveled or suitably cut, so as to rest or have a bearing on each of the cross-bars, and thus assist in the equalization and distribution of the weight, so as to bring the strain farther from the top of the swing, thus preventing that objectionable lateral movement so common in other swings. Small links 8, located near the end of each of the vertical standards, pivotally connect said vertical standards and cross-bars at 9 and 10, and thus hold the bevel end of said vertical standards in position on said cross-bars and at the same time permit

of the parts coming together when being folded, as shown in Fig. 4.

Extending transversely across near the top of the swing at either end are the upper brace-
5 rods 11, which pass through near the upper ends of cross-bars 1 and vertical standards 7 and are held in position by a nut and washer 12. Said upper brace-rods assist in retaining or holding the swing parts together in proper
10 position, as shown in Figs. 1, 2, and 3.

Pivotedly mounted at their tops on brace-
15 rods 11 are the swinging arms or members 13, two of which are located at each end of the swing, being held apart near their tops by a
20 brace 14, while at their lower ends they are pivotedly connected or hinged to the two sections 15 of the swinging platform by lower
25 brace-rods 16, said lower brace-rods being retained in position by a nut and washer 17 in
30 a similar manner to the central and upper
brace-rods.

Platform-sections 15 comprise the side strips 18, pivotedly mounted at their ends on lower
35 brace-rods 16 and being provided across their
tops with numerous slats 19, which make up the platform or foot-rest proper, said platform-sections being pivotedly hinged and joined at a central point 20 in any suitable
40 manner, so as to break joints, (see Fig. 5,) thus allowing all the parts to come together when the swing is folded in position, as shown in Fig. 4.

At each end of the swing is located a chair, each of said chairs comprising a slotted seat
35 portion 21, having suitably-formed legs or supports 22, provided with a brace 23 (see Fig. 3) and formed with suitably-slotted ends 24, adapted to engage or disengage the lower
40 brace-rods 16 when supporting the seat or when the swing is being folded, as shown in Fig. 4, the upper end of said legs or supports forming a pivotal connection at 25 with the inner or forward ends of the side portions 26 of the chair, while the outer or rear end of
45 side portions 26 in turn form pivotal connections at 27 with the side members or portions 28 of the suitably-formed chair-back 29. Said member 28 extends down in the form of standards or legs also and forming a slotted connection with lower brace-rods 16, and thus
50 supports the back of the chair. Side arms 30 extend horizontally one on each side of the chair and are pivotedly connected at one end to the swinging members 13 and are provided
55 with a longitudinal slot 31, which receives a pin 32, preferably formed with a head, said pin projecting from the members 28 of the chair-back 29, side arms 30 being provided with a number of small openings 33, adapted
60 to receive a pin 34, connected to the end of a chain or cord 35, which is conveniently attached in any suitable manner to side member 28. Said pin 34, passing through the openings 33 and having a bearing against pin 32,
65 permits the chair-back 29 to be inclined in different positions, as desired.

A very important feature about my swing

and one which makes it less expensive than others consists in the construction and arrangement so that it will not be necessary 7c to remove any bolts or nuts, nor the platform, nor, in fact, any of the parts when it is desired to fold said swing for storage or transportation.

It will of course be understood that slight 75 changes or modifications of the various parts may be made without departing from the spirit or principles of my invention.

Having thus described my swing, what I claim as new and of my invention is—

1. The combination in a folding swing, with the supporting-frame thereof; of the swinging arms pivotedly connected to said supporting-frame; a platform pivotedly connected to said swinging arms, and formed of sections or foot-rests, pivotedly connected or hinged together so as to break joints one with the other; the folding seats, each provided with a suitable back portion and legs or standards pivotedly and detachably supported, so as to permit 90 said swing to fold without the removal or disconnection of any of the parts.

2. In a folding swing having a supporting-frame and swinging arms; the chairs or settees each comprising the following elements, 95 viz: the seat portion 21; the legs or supports 22 connected by a brace 23, said legs formed with slotted ends 24 and pivotedly connected to, and supporting the forward end of said seat portion; the back portion, provided with 100 the side members 28, which have a pivotal connection with the rear end of said seat portion, and depend and form the legs or standards having slotted ends; both forward and rear sets of legs having their slotted ends detachably meeting at one point; the straight and slotted side arms 30, adjustably connected to said back portion so as to incline said chairs or settees; all adapted to be knocked down and folded together, substantially as and for 110 the purpose described.

3. The combination in a folding swing with the chairs or seats thereof; of the inclined cross-bars, which support the swing, and intersect or cross each other in the form of a 115 "sawbuck," the central brace-rod which pivotedly connects said cross-bars, in the manner of a hinge; the vertical standards pivotedly supported at their tops, and having a bearing and resting at their lower ends on said cross-bars; the links which connect said cross-bars and vertical standards; the swinging or hanging arms, so pivotedly connected at their tops with the supporting cross-bars, as to oscillate or swing; the platform or foot-rests, formed of hinged sections and pivotedly supported at each end; the whole being suitably braced and adapted to fold up without the removal of any of the parts; substantially as and for 125 the purposes specified.

4. The combination in a swing, of the supporting cross-bars, which intersect or cross each other in the form of a "sawbuck;" the transverse braces connecting each set of cross-

bars at their lower ends or base; the short upright braces which extend up a suitable distance from the base, and connect with each of the cross-bars; the central brace-rod which 5 pivotally connects each set of cross-bars; the vertical standards pivotally supported and connected at their tops by a brace-rod, and having a bearing, and resting at their lower ends on said cross-bars; the links which connect 10 said cross-bars and vertical standards; the swinging or hanging arms so pivotally supported and connected at their tops by the brace-rod and the cross-bars, as to oscillate or swing; said brace-rod which pass through 15 near the tops of, and pivotally support and connect the cross-bars, vertical standards and

swinging arms; the platform or foot- rests, pivotally supported at each end to the swinging arms, and formed of hinged sections; the folding chairs or settees pivotally connected 20 to said swinging arms having straight side arms, and legs or standards formed with slotted ends; all adapted to knock down and fold together without the removal of any of the parts; substantially in the manner and for the 25 purpose described.

In testimony whereof I have affixed my signature in presence of two witnesses.

WILLIAM HITT BOGGS.
